(57) **CLAIM**

The ornamental design for a pyramid corner connector for wall panel system, as shown and described.

DESCRIPTION

FIG. 1 is a first perspective view of a pyramid corner connector for a wall panel system showing our new design. FIG. 2 is a second perspective view thereof.

FIG. 3 is a front plan view thereof.

FIG. 4 is a rear plan view thereof.

FIG. 5 is a top plan view thereof.

FIG. 6 is a bottom plan view thereof.

FIG. 7 is a right side elevation view thereof; and,

FIG. 8 is a left side elevation view thereof.

1 Claim, 4 Drawing Sheets
